UNITED STATES PATENT OFFICE.

WARREN B. HOWE, OF CHICAGO, ILLINOIS.

PAPER BOX.

SPECIFICATION forming part of Letters Patent No. 329,562, dated November 3, 1885.

Application filed July 22, 1885. Serial No. 172,283. (No model.)

To all whom it may concern:

Be it known that I, WARREN B. HOWE, of Chicago, in the county of Cook and State of Illinois, have invented certain new and useful 5 Improvements in Paper Boxes; and I do hereby declare that the following is a full, clear, and exact description thereof, reference being had to the accompanying drawings, and to the letters of reference marked thereon, 10 which form a part of this specification.

This invention relates to improvements in that class of paper or straw-board boxes or canisters which are provided in one of their sides or walls with a filling-orifice and a hinged 15 flap or cover to close the latter; and it consists in the matters hereinafter described, and pointed out in the appended claims.

A principal feature of the invention relates to means for opening the said flap or lid when held in its closed position by pasting over it a sheet of paper or label; and it consists in a 20 string or strings attached to the lid or the box, and passing thence within the box, and having its free end or ends extended out of the box 25 between the edge of the lid and that of the box-wall, whereby the string may be seized and drawn around the cover by the hand applied to the said free end or ends, so as to sever the paper covering or label along the 30 joint between the cover and box, and thereby allow the cover to be readily opened.

The invention also embraces, in combination with a hinged lid, covering-sheet, and opening-string, a ledge or support formed about the 35 filling-orifice for sustaining the lid flush with the box-wall in pasting on the covering-sheet, and it embraces also an improved means of constructing such ledge or support, as will hereinafter appear.

40 The invention may be more fully understood by reference to the accompanying drawings, in which—

Figure 1 is a perspective view of the upper part of a box, showing the cover or flap open and the string in the position usually occupied 45 by it when the cover is closed. Fig. 2 is a similar perspective view showing the cover closed and a paper sheet or label pasted over it, the string being shown as partially drawn around one side of the cover to illustrate the 50 operation of the said string in opening the box. Fig. 3 is a perspective view showing

one end or wall of a box having the hinged lid therein and separated from the adjacent walls, this figure illustrating more particularly 55 one means of constructing the ledge for supporting the lid shown in Fig 1, and above referred to. Fig. 4 is a plan view of a box made as shown in Figs. 1, 2, and 3, a part of the top or end wall being shown as broken 60 away to illustrate the construction of the box. Fig. 5 is a detail section of the upper portion of the box, taken upon line xx of Fig. 4. Fig. 6 is a similar sectional view illustrating another practicable way of making the joint between the top and sides of the box. Fig. 7 is a detail view from beneath or inside of the top provided with a hinged flap or lid, showing a cloth strip applied to strengthen the hinged joint and to hold the string in place. 70 Fig. 8 is a plan view of a box, illustrating a flap or cover of circular form, together with an opening-string having but one end exposed outside of the box. Fig. 9 is a perspective view having a part of the outer sheet or label 75 broken away, illustrating a flap or cover as applied to overlap the adjacent parts of the box-wall.

In the particular construction of the device shown in the drawings, A indicates the box, 80 of which A' is the top or side containing the filling-opening, and A² are the adjacent side walls. B is the hinged flap for closing said opening. C, Fig. 2, is a paper sheet or label pasted over the cover and adjacent parts of 85 the box-wall to hold the cover closed when the box has been filled and is ready for transportation or sale, and D is a string or cord which is attached to the inner surface of the box or cover near the hinged joint of the latter, 90 the end or ends of said string being extended through the joint between the lid and the box-wall to the outside of the latter, so that when the paper sheet C is pasted down over the cover the said sheet may be torn or severed 95 along the edge of the cover by grasping the end of the string and carrying it around from the point at which it is laid when the sheet is pasted over it to the hinged joint of the cover at either side of the said hinged joint. Either 100 a single or a double string may be used, and it may be attached to the inner surface of the box in any manner found convenient or desirable. As shown in the figures from 1 to 6,

the string is double, a single piece of string being used, which is attached at its middle to the box, and the free ends of which are brought together through the joint between the box and cover when the latter is closed. When this construction is used, the ends of the string will usually be laid over the marginal part of the box-wall at a point opposite the hinge of the flap, and the paper sheet C is severed at one side of the flap by the use of one part of the string, and at the opposite side of the flap by the other part. As shown in Fig. 7, however, a single string is used, which is secured at one end to the box and at its opposite end extends between the edge of the cover and the box-wall, and may be carried around in the crack between the box-wall and cover at both sides of the latter so as to sever the paper sheet in the same manner as before set forth. One simple means of securing the string D to the box is shown in Figs. 1 and 2, in which the middle part of the string is looped and tied around the hinged joint of the cover, the knot in the string being located beneath the cover, so that the string will be held at its inner part when its outer or free ends are carried around the edges of the lid in the manner above set forth. When the cover is made with a neck, b, at its hinged point narrower than the flap, and an abrupt shoulder is thereby formed, as indicated at b', the string may be placed around the neck without being tied, as indicated in Figs. 3, 4, and 7, the abrupt shoulders preventing the displacement of the string when its ends are manipulated as above set forth.

In the case of straw-board boxes, the board of the top is usually partially cut through or scored at the hinged joint, in order to enable the lid to readily open, and in such case a cloth strip may sometimes be pasted over the joint, either upon the inner or outer surface of the cover and lid, as shown, for instance, in Fig. 7, in which the strip is shown as applied to the inner face of the top. The said cloth strip, when employed, may be desirably applied after the string D has been placed around the neck b, and said strip may in such case be arranged to cover the parts of the string adjacent to the neck, as clearly shown in said Fig. 7 and in Fig. 3, in which a cloth strip is shown as applied at the outer surface of the box over the string, so as to firmly hold the string in place without other fastening.

As illustrated in Fig. 8, the top A' of the box is provided with two small apertures, a, through which the string is passed and then tied upon the inside of the box. This means of fastening may obviously be applied as well to the double string shown in Figs. 1 and 2 as to the single string illustrated in said Fig. 8.

It will be observed that in the means for fastening the string shown in Figs. 1, 2, 3, and 4 and in Fig. 8 the sheet or label C will be pasted upon or over the string, and in these cases and in any case in which the string is partially located

at the outer surface of the box the said sheet or label may be relied upon, either wholly or partially, as a means of attaching the string. It will be seen, furthermore, that in the case when the string is merely placed around the neck or hinge of the cover without tying, as shown Fig. 4, the outer or free ends of the said string may be crossed, so that a person opening the box will draw each end of the string around the side of the lid opposite to the side at which the inner part of the said end is fastened, whereby when the string has been drawn back to the rear edge of the lid the string will be looped about the neck b, and thereby held more firmly instead of being loosened, as would be the case if the strings were drawn in the opposite direction. By arranging the strings as shown in Fig. 4, therefore, any particular means for attaching the string to the box may be dispensed with. The presence of the paper sheet or label in this and all other cases where the string passes outside of the lid tends of course to hold the string in place, as above set forth.

In the several forms of the flap described the latter has been arranged in such manner as to shut down flush with the box-wall, so that the top of the box will be flat, or present no ridge or irregularity after the covering-sheet or label has been pasted over the cover. The string D, operating as above set forth, may, however, be applied in cases in which the lid is otherwise constructed—as, for instance, when the form of cover shown in Fig. 9 is used. In this case the cover B is made larger than the orifice in the box, and is applied to overlap the margins of the said orifice, the string D being attached near the hinge of the lid and the label pasted over the lid so as to hold the latter closed in the manner before described. The string in this case may be attached in either of the ways before mentioned or by any other convenient means—as, for instance, it may be pasted under a cloth strip, H, Fig. 9, employed to form the hinge between the lid and box-wall. In this construction it will be noted that the string is fastened upon the outside of the box and passes beneath the cover or lid at the sides of the hinge thereof.

From what has been stated above it will be apparent that the particular construction in the flap or the hinged joint, or in the means for attaching the string to the box wall or cover, is unimportant. It is entirely obvious in this connection that the covering-sheet may sometimes be alone relied upon to form the hinged joint between the lid and box.

The form of the cover and manner of attaching the string will be determined in any particular case by the kind of box to which the said devices are to be applied, the essential feature of the device being a string attached so that it may be carried around the edge of the flap to sever the covering-sheet, as above set forth.

The flap and string, constructed generally as above set forth, may obviously be employed

in connection with boxes of any kind or shape, and my invention, as it relates to this part of the device, is not therefore limited to any particular construction in other parts of the box. The particular box shown, however, embodies improvements in the construction thereof in its parts adjacent to the filling-orifice and flap as follows: Upon the under or inner side of the top or wall A', in which the filling-orifice is formed, are glued, pasted, or otherwise secured strips of pasteboard or other material which are constructed to project inwardly beyond the margins of the orifice, at one or more sides of the latter, so as to form ledges or supports F, against which the lid will strike when closed, and which will operate to sustain the lid flush with the wall of the box, and prevent its being depressed or thrust into the box under the pressure used to paste down or over it the paper-sheet C. Said ledge or support is, however, useful in cases where the paper-sheet is absent, or where the cover is secured otherwise than by the said sheet, and the appended claims upon the ledge are not limited to its use in connection with the sheet as a means of fastening the cover and the opening-string, except as herein specifically claimed.

A preferable construction whereby the ledges or supports F may be readily formed in making the box is illustrated in Figs. 1, 2, 3, and 4, in which the marginal portions of the side walls, A², of the box adjacent to the top or end wall, A', are bent inwardly at right angles to the said side walls, as indicated at f, Figs. 3 and 4, the said inwardly-bent portions being of sufficient width to extend inwardly past or overlap the side margins of the orifice in the wall A', so that when the said top wall is placed upon and pasted to the said inwardly-bent parts ledges or supports F will be formed, as above set forth. This construction affords a simple and convenient means of uniting the end or top wall to the side walls of the box, inasmuch as by it the inwardly-bent parts may be readily pressed against the top for the purpose of fastening them by inserting the fingers through the filling-orifice. The ledge or support F, as far as the appended claim covering said ledge in combination with the covering-sheet and string is concerned, may, however, be formed otherwise than above set forth—as, for instance, the construction shown in Fig. 6 may be used, in which the marginal parts of the top A' are bent downwardly and inserted between the side walls, A², and the said ledges are formed by separate strips f, properly glued or pasted to the under surface of the top.

It is to be understood that the appended claims cover the parts or elements therein set forth when said parts or elements are in form

to obtain either, any, or all of the purposes, functions, objects, or advantages obtained by or belonging to them in the particular form 65 thereof herein illustrated.

I claim as my invention—

1. A paper box or canister provided with a filling-orifice in one of its walls, a hinged cover or lid for covering said orifice, and a 70 string attached to the box or lid and capable of extending across the lid beneath the same and out of the box between the lid and box-wall, substantially as described.

2. A paper box or canister provided with a 75 filling-orifice in one of its walls, combined with a hinged cover or lid for closing said orifice, a sheet or label secured to the box over said lid, and a string secured at one end to the box or lid, said string extending within the 80 box and emerging therefrom between the lid and the box-wall, whereby said string may be employed to sever the covering sheet or label, substantially as described.

3. A paper box or canister provided with a 85 filling-orifice in one of its walls, combined with a hinged cover or lid fitted within said orifice for closing it, a sheet or label secured to the box over the lid, and a string attached at one end to the box or lid, said string extending within the box and emerging therefrom between the lid and the box-wall, whereby said string may be employed to sever the covering sheet or label, substantially as described. 95

4. A paper box or canister having a wall, A', provided with a filling-orifice, and a hinged cover or lid for closing said orifice, and having the margins of its side walls adjacent to the wall A' bent inwardly and constructed to 100 extend past the margin or margins of the orifice and secured to the said wall A', substantially as described.

5. A paper box or canister having a wall, A', provided with a filling-orifice, and a hinged 105 cover or lid fitted within the orifice, and having a strip of pasteboard or other material secured to the inner surface of said wall and extending beyond the margin of the orifice to form a ledge or support for the lid, combined 110 with a paper sheet or label secured over the lid, and a string or its equivalent attached at one end to the box or lid and extending within the box, and emerging therefrom between the lid and the box-wall, whereby said string may 115 be employed to sever the covering-sheet, substantially as described.

In testimony that I claim the foregoing as my invention I affix my signature in presence of two witnesses.

WARREN B. HOWE.
